CAM CONTROLLED STRETCH FORMER

Burt F. Raynes, Chula Vista, Calif., assignor to Rohr Aircraft Corporation, Chula Vista, Calif., a corporation of California

Application February 15, 1954, Serial No. 410,229

4 Claims. (Cl. 153—40)

This invention relates to a means for accurately controlling the amount of stress applied to a workpiece while it is being formed in a metal forming machine of the type wherein the workpiece is first stressed a predetermined amount and then formed while under tension by being wrapped along the face of a forming die.

When forming metal on a machine of the aforementioned type, it has been customary to test a sample of the material to be formed to determine the amount of tension which must be applied to the workpiece to stress it to its elastic limit. The necessary amount of tension, as determined from this test, is applied to the workpiece which is then wrapped along the face of a forming die to form it to a desired shape. In actual production practice, however, it has been found that the amount of tension required to stress a given number of workpieces of the same size and material to their elastic limits, may vary greatly. For instance, it has been found that one piece may require the application of a 40,000 pound force to stress it to its elastic limit while another piece may require as much as 60,000 pounds force to stress it to its elastic limit. In order to produce satisfactorily formed parts in a situation such as this, it would be necessary to test each workpiece to determine what tension must be applied to stress it to its elastic limit, a procedure obviously prohibitive from a cost and manufacturing standpoint. If, as an alternative, an average force is taken as a norm, as for example 50,000 pounds, it will result in some of the workpieces being greatly overstressed and others understressed, resulting in a complete lack of uniformity in the finished parts and rendering many of them useless. Also, since in many instances the yield strength and the ultimate strength of a workpiece are relatively close values, it follows that any appreciable amount of over stressing of a workpiece will result in failure of the material and ruining the workpiece.

While the amount of tension required to stress each of a number of workpieces of the same size and material to their elastic limits may vary greatly, it has been found that the elongation of each workpiece when stressed to its elastic limit, is very nearly the same. It therefore follows that by determining the amount of elongation required to stretch a hard workpiece to its elastic limit, all other workpieces of similar size and material whether in high or low tensile range of hardness may be stretched to their elastic limit by a substantially like amount of elongation despite the variation in the amount of force required by each workpiece.

It is, therefore, the primary object of my invention to provide a control means for use on a machine of the aforementioned type, to regulate the elongation of a workpiece to an amount sufficient to stress it a desired amount and to maintain a proportional amount of elongation in proportion to the length of the unformed portion of the workpiece throughout the forming operation.

A further object is to provide a control means as beforementioned which is adaptable for use on all types of

2

forming machines in which tensile stress is applied to a workpiece while it is being formed.

A further object is to provide a control means as above described which is simple and inexpensive to manufacture and which may be quickly and easily installed on a forming machine.

These and other objects and advantages will become apparent as the description of the invention proceeds.

My invention consists primarily of a cam control 10 which is designed to operate in conjunction with the forming die to regulate the amount of tension applied to the workpiece by the tensioning device, prior to and during the forming operation, to permit the workpiece to be elongated a distance sufficient to stress it the desired 15 amount at all times. The shape and size of the cam is governed by the shape of the forming die with which it is used and the size and material of the workpiece to be formed.

For a better understanding of the invention, attention 20 is directed to the accompanying drawing illustrating several preferred embodiments of the invention and in which:

Figure 1 is a front view of a forming machine having a hydraulic tensioning device regulated by a cam secured to and rotatable with a rotary table on which the forming 25 die is mounted.

Figure 2 is a top view of the machine of Figure 1.

Figure 3 is a schematic view partly in section of a portion of the machine of Figure 1 showing its hydraulic system controlled by a cam.

Figure 4 is a top view of a forming machine employing two hydraulic tensioning devices which pivot about a stationary forming die, each of the tensioning devices being controlled by a cam mounted in a stationary position adjacent the die.

Figure 5 is a front view of the machine of Figure 4. Figure 6 is a top view of a forming machine in which the workpiece is stressed by rotation of a rotary table, illustrating a cam control for regulating the amount of stress applied during the forming operation.

Figure 7 is a front view of the machine of Figure 6.

Figure 8 is a top view of a forming machine wherein one end of the workpiece is held in a stationary chuck while the workpiece is drawn along the face of a stationary forming die by a tensioning device equipped with a control valve which regulates the elongation of the workpiece.

Figure 9 is a view, partly diagrammatic, illustrating the attachment of the tensioning device control valve.

Referring to the drawing, the forming machine illustrated in Figures 1 and 2 comprises a base 10 having a rotary die supporting table 11 which may be slowly rotated by a known power means as, for example, a worm and worm gear (not shown) and on which is mounted a suitably shaped forming die 12. A chuck 13 is pivotally connected to table 11 and adapted to grip the end 14 of a workpiece 15. A cam 16 secured to and rotatable with table 11 has a suitably curved face 17 whereby the tension applied to the workpiece is controlled in a manner to be later explained. A hydraulic cylinder 18 is attached to a vertical shaft 9 pivotally supported in a frame 8 attached to base 10 and contains a piston P. The piston is connected to the end of a piston rod 19 which has a chuck 20 attached to the other end thereof and adapted to grasp the end 21 of workpiece 15, and serves as a means for applying tension to workpiece 15. Oil or other fluid under pressure is supplied to the head end of cylinder 18 through a conduit 22 connected to a suitable supply tank (not shown). Fluid under pressure is supplied to the rod end of cylinder 18 by a supply pipe 23 connected to the supply source through a control valve 24 attached to chuck 20. Fluid connection is established between pipe 23 and valve 24 through pipe 25, valve 26

and pipe 27 opening into the lower side of valve 24. Fluid connection between the rod end of cylinder 18 and valve 24 is established through pipes 28 and 29, valve 30, pipe 31 and branch pipes 32 and 33 which open into the upper side of valve 24. A fluid return pipe 34 extending from the lower side of valve 24 conveys fluid from cylinder 18 and valve 24 back to the fluid supply tank. Fluid connection between pipe 23 and the rod end of cylinder 18 may also be made through a valve 35, pipe 29 and pipe 28.

Valve 24 which controls the fluid in the rod end of cylinder 18 in a manner to be later explained, is comprised of a cylindrical body 36 which slidably contains a piston 37 connected to a cam follower 38. Piston 37 is provided with two fluid passing grooves 39 and 40 which are adapted, upon movement of piston 37, to connect the openings of pipes 27 and 32 and the openings of pipes 33 and 34 respectively. Grooves 39 and 40 are so spaced apart that both cannot be connected with the pipe openings simultaneously. Piston 37 is normally held in a position as shown in Figure 3 in which groove 40 connects the opening of pipe 33 with the opening of pipe 34, under the bias of a spring 41 contained in the end of valve body 36.

In operating the forming machine equipped with the cam control, valves 30 and 26 are closed and valve 35 is opened to admit fluid under pressure to the rod end of cylinder 18 moving piston P and piston rod 19 toward the head end of cylinder 18 to a position as shown in Figure 1. Valve 35 is then closed and valves 26 and 30 are opened. Table 11 is rotated in a clock-wise direction until chuck 13 is brought to a position sufficiently near chuck 20 to permit ends 14 and 21 of workpiece 15 to be gripped by chucks 13 and 20 respectively. Two marks may previously be made near the ends of the workpiece to indicate the length of the portion to be inserted in each chuck, the distance between these marks being the same on all workpieces to be bent to the same shape. Table 11 is then rotated in a counter-clockwise direction as indicated by arrow A in Figure 2, moving chuck 13 away from chuck 20. As table 11 rotates and workpiece 15 is drawn away from cylinder 18 it draws with it chuck 20 and piston rod 19 and moves piston P toward the rod end of cylinder 18, the fluid in the rod end of the cylinder being permitted to escape through pipe 28, valve 30, pipes 31 and 33, groove 40 in piston 37 and pipe 34. As chuck 20 approaches table 11, cam follower 38 comes into engagement with face 17 of cam 16 moving piston 37 in valve 24 to the left thus moving groove 40 out of alignment with the opening of pipes 33 and 34 and stopping the escape of fluid from cylinder 18. The fluid remaining in the rod end of cylinder 18 will prevent any further movement of piston P, piston rod 19 and chuck 20 toward table 11 and the continued rotation of table 11 moving chuck 13 away from chuck 20 will apply the tension necessary to elongate workpiece 15. When table 11 has rotated to the position where workpiece 15 is in contact with the face of die 12 as shown in Figure 2, the workpiece will be elongated an amount sufficient to stress it the desired amount prior to wrapping it along the curved face of die 12. The further rotation of table 11 then wraps workpiece 15 along the face of die 12 to form it to the desired shape.

To prevent an increase in tension and consequent overstressing of workpiece 15 as it is wrapped around die 12 by the rotation of table 11, it is necessary to permit piston P, piston rod 19 and chuck 20 to move outwardly toward table 11 during the forming operation. To accomplish this the contour of cam face 17 is such that as cam 16 rotates with table 11 and face 17 passes along cam follower 38 it permits cam follower 38 and piston 37 to move outwardly, to the right, under the bias of spring 41. This movement of piston 37 brings groove 40, or a portion thereof, into alignment with the open-

ings of pipes 33 and 34 allowing fluid to bleed off from the rod end of cylinder 18 through pipe 28, valve 30, pipe 31, branch pipe 33, groove 40 and pipe 34, permitting piston P to be drawn toward the rod end of cylinder 18. The position of piston 37 is so controlled by the contour of cam face 17 that the rate at which fluid passes through groove 40 is such that piston P is constantly in a position in relation to workpiece 15, so that workpiece 15 is continually elongated by an amount which is in direct proportion to its unformed length, throughout the forming operation.

With reference to Figures 4 and 5 of the drawing, the forming machine therein illustrated employs two hydraulic tensioning devices, both of which are similar in all respects to the one previously described herein and illustrated in Figure 3. Each of the tensioning devices is controlled by a cam and for reasons of clarity the second tensioning device and the second cam are herein designated by primed numbers.

The machine consists of a main body member 42 having a pair of carrier arms 43 and 44 pivotally attached thereto at pivots 45 and 46. A pair of draw bars 47 and 48 extending from arms 43 and 44 respectively are connected to a suitable power source (not shown) and provide means for swinging arms 43 and 44 about pivot points 45 and 46 toward body 42. Forming die 12 is mounted in a stationary position at the end of body 42 between and above arms 43 and 44. Hydraulic cylinder 18 is mounted on carrier arm 43 with the rod end of the cylinder toward die 12. A second hydraulic cylinder 18¹ is mounted on carrier arm 44 with the rod end toward die 12. Cam 16 is mounted on main body member 42 adjacent the side of die 12 in a stationary position with the cam face 17 toward cylinder 18. The second cam 16¹ is secured in a similar manner on the opposite side of die 12 with its face 17¹ toward cylinder 18¹. Cam faces 17 and 17¹ are both provided with a rising contour at points 49 and 50 for a purpose to be later explained.

To operate the machine, fluid under pressure is directed to the head ends of cylinders 18 and 18¹ moving pistons P and P¹ toward the rod ends of the cylinders and advancing piston rods 19 and 19¹ and chucks 20 and 20¹ toward each other until cam followers 38 and 38¹ engage cam faces 17 and 17¹ as shown in Figure 5. The size of cams 16 and 16¹ is such that the distance between chucks 20 and 20¹ when in this position permit ends 21 and 14 of workpiece 15 to be gripped by chucks 20 and 20¹ respectively. Valves 35 and 35¹ are then closed and valves 30, 30¹, 26 and 26¹ opened and fluid under pressure is directed from pipe 23 to control valves 24 and 24¹ through pipes 25 and 25¹, valves 26 and 26¹ and pipes 27 and 27¹. Power is then applied to draw bars 47 and 48 to swing arms 43 and 44 about pivots 45 and 46 toward body 42 to wrap workpiece 15 along the curved face of die 12. As the arms move, cam followers 38 and 38¹ pass along cam faces 17 and 17¹. In so doing they encounter the rise in the contours of faces 17 and 17¹ at points 49 and 50 at approximately the same time that workpiece 15 comes into contact with the face of die 12. The rise in the contours forces cam followers 38 and 38¹ and pistons 37 and 37¹ outwardly a distance sufficient to cause grooves 39 and 39¹ to come into alignment with the openings of pipes 27 and 32 and 27¹ and 32¹. This permits fluid under pressure to pass through grooves 39 and 39¹ from pipes 27 and 27¹ into pipes 32, 31 and 31¹, through valves 30 and 30¹ and pipes 28 and 28¹ into the rod ends of cylinders 18 and 18¹ thereby moving pistons P and P¹ toward the head ends of cylinders 18 and 18¹. As pistons P and P¹ move, they cause chucks 20 and 20¹ to move away from each other and apply tension to workpiece 15, the control valves 24 and 24¹ also moving away from cam faces 17 and 17¹. This permits cam followers 38 and 38¹ to

move inwardly under the bias of springs 41, thus moving grooves 39 and 39¹ out of alignment with the openings of pipes 27 and 32 and pipes 27¹ and 32¹ and stopping the admission of fluid under pressure to the rod ends of cylinders 18 and 18¹. The rising contours of cam faces 17 and 17¹ are such that they regulate valves 24 and 24¹ to admit the proper amount of fluid under pressure to cylinders 18 and 18¹ to cause pistons P and P¹ to apply sufficient tension to workpiece 15 to elongate it the desired amount. As arms 43 and 44 continue to move toward body 42, workpiece 15 is wrapped along the face of die 12 and cam followers 38 and 38¹ moving along cam faces 17 and 17¹ control valves 24 and 24¹, in the manner previously explained, to regulate the amount of stress applied to the workpiece throughout the forming operation. The workpiece is continually stretched an amount which is directly proportional to the length of its unformed portion.

Referring to Figures 6 and 7, the forming machine illustrated therein comprises a base 10 having a rotary die supporting table 11 which may be rotated by a known power means (not shown) and on which is mounted on table 11 the chuck 13 adapted to grip the end 14 of workpiece 15. A heavy cam 16 having a curved face 17 is secured to table 11 by bolts 51. A sleeve 52 pivotally mounted on base 10 slidably contains a shaft 53 to one end of which is secured a chuck 20 adapted to grip the end 21 of workpiece 15. A cam follower 54 adapted to engage cam face 17 is mounted on shaft 53 adjacent chuck 20.

To operate the machine table 11 is rotated in a clockwise direction until chuck 13 is brought into a position sufficiently near chuck 20 so that ends 14 and 21 of workpiece 15 may be gripped by chucks 13 and 20 respectively. Table 11 is then rotated in a counterclockwise direction as indicated by arrow A in Figure 6, moving chuck 13 away from chuck 20. As table 11 rotates moving chuck 13 away from chuck 20, shaft 53 and chuck 20 are drawn toward table 11 by workpiece 15 until cam follower 54 engages cam face 17 preventing any further forward motion of chuck 20 and shaft 53. The continued rotation of table 11 moving chuck 13 away from chuck 20 applies the tension necessary to elongate workpiece 15. When workpiece 15 is in position to contact die 12, as shown in Figure 6, it will be elongated an amount sufficient to stress it the proper amount prior to wrapping it along the face of die 12. As table 11 continues to rotate, wrapping workpiece 15 along the curved face of die 12, the contour of cam face 17 is such that chuck 20 and shaft 53 are permitted to advance toward table 11 at a rate which will maintain the elongation of workpiece 15 constantly in direct proportion to its unformed length during the forming operation.

Referring to Figures 8 and 9, the forming machine illustrated is similar in construction to that previously described and illustrated in Figures 4 and 5. It consists of a main body member 42 having a pair of carrier arms 43 and 44 pivotally attached to one end thereof to pivots 45 and 46. A pair of draw bars 47 and 48 extending from arms 43 and 44 respectively, are connected to a suitable power source (not shown) to provide means for moving arms 43 and 44 about pivot points 45 and 46 toward body 42. Forming die 12 is mounted on the end of body 42 in a stationary position between and above arms 43 and 44. A chuck 13 adapted to grip the end 14 of workpiece 15 is pivotally mounted on arm 44. A hydraulic cylinder 18 is pivotally mounted on arm 43 and contains a piston P connected to a piston rod 19 to one end of which is attached a chuck 20 adapted to grip the end 21 of workpiece 15. Fluid under pressure is supplied to the head end of cylinder 18 through a pipe 22 connected to a suitable fluid supply source (not shown) and to the rod end of cylinder 18 through a pipe 23 and a control valve 56. Fluid connection is established between pipe 23 and valve 56 through pipe 25 and valve 26

and between valve 56 and the rod end of cylinder 18 through pipe 57. Valve 56 is of a known type which is normally opened and closed by pressure against a control lever 58. Valve 56 is adjustably supported on the end of cylinder 18 by a rod 59 slidably mounted in an opening in a bracket 60 which is secured to cylinder 18 and a lock screw 61 serves to engage rod 59 to lock it in adjusted position.

To operate this machine, fluid under pressure is directed by pipe 22 to the head end of cylinder 18 to move piston P to the rod end of the cylinder and move chuck 20 sufficiently near chuck 13 so that ends 14 and 21 of workpiece 15 may be gripped by chucks 13 and 20 respectively. Arms 43 and 44 are then simultaneously moved about pivot points 45 and 46 toward body 42 to positions which permit full contact between workpiece 15 and the face of die 12 as shown in Figure 8. Fluid under pressure is then directed to the rod end of cylinder 18 from pipe 23 through 25, valve 26, control valve 56 and pipe 57 causing piston P to move toward the head end of cylinder 18 and retract rod 19 and chuck 20 to apply tension to workpiece 15 and stretch it. Valve 56 is set in an adjusted position so that when workpiece 15 has been elongated sufficiently to provide the proper amount of stress to force it to conform to the shape of die 12, chuck 20 will come in contact with control lever 58 and move it, thus closing valve 56 which stops the passage of fluid into cylinder 18. The movement of piston P is thus arrested when the workpiece has been elongated the proper amount.

In each form of the invention, the length of workpiece between the chucks gripping its ends, before stretching, is kept the same for all workpieces to be bent to the same shape.

The fluid used in the hydraulic systems of the above described machines is preferably a liquid such as oil and the pipes conveying the liquid to moving parts of the machines are composed of flexible material.

This invention may be embodied in other forms or carried out in other ways without departing from the spirit or essential characteristics thereof. The present embodiment of the invention is therefore to be considered as in all respects illustrative and not restrictive, the scope of the invention being indicated by the appended claims, and all changes which come within the meaning and range of equivalency of the claims are intended to be embraced therein.

Having thus described my invention, what I claim as new and useful and desire to secure by Letters Patent is:

1. A forming machine adapted to form a long workpiece to a desired curvature comprising, in combination: a rotary table; a die having a curved face supported on said table; means adjacent one end of said die connecting one end of the workpiece to said table; means for rotating said table to wrap the workpiece along said die face; a jaw gripping the other end of the workpiece; a fluid containing cylinder; means for supporting said cylinder so as to prevent movement thereof toward said die; a piston slidable in said cylinder and connected to said jaw; an outlet including a movable valve for permitting the escape of fluid from the end of said cylinder adjacent said table; and means including a curved cam carried by said table and constructed to control said movable valve to permit the passage of fluid through said outlet at a desired rate as the table is rotated.

2. A forming machine adapted to conform a long workpiece to a desired curvature comprising, in combination, a die having a face conforming to said curvature, means including a pair of jaws respectively gripped to the ends of the workpiece and spaced from said die for holding the unformed workpiece initially away from the die, a cylinder, a piston connected to one of said jaws and slidable in said cylinder, means supporting said cylinder and die for relative rotation therebetween sufficient to bring the workpiece into contact with the die

and to wrap the workpiece along said face of the die, means for causing said relative rotation between said cylinder and die, and workpiece tensioning means including said piston and cylinder and a cam and follower therefor carried respectively by said die and said one of the jaws for resisting movement of said piston toward the die as said one of the jaws and the portion of the workpiece gripped thereby are drawn toward the die in response to movement of the workpiece into contact with the die and subsequent wrapping thereabout, said cam having a curved face and said follower being constrained by said tensioning means to contact and follow along said face of the cam as the workpiece is brought into contact with and wrapped along said face of the die, said cam face being shaped to control initial stretching of said workpiece by said tensioning means prior to contacting of the workpiece with the die, said cam face being further shaped to control continual elongation of the workpiece by said tensioning means in proportion to the length of the unwrapped portion of the workpiece as the workpiece is wrapped along the face of the die, said tensioning means including a valve carried by said one of the jaws and having a spring biased plunger movable under control of said follower to a first position for preventing release of fluid under pressure by said piston in said cylinder and to a second position for releasing said fluid from the cylinder to permit movement of the piston toward the die.

3. A forming machine adapted to conform a long workpiece to a desired curvature comprising, in combination, a rotary table, a die having a face conforming to said curvature and supported on said table for rotation therewith, means including a pair of jaws respectively gripped to the ends of the workpiece and spaced from said die for holding the unformed workpiece initially away from the die, a cylinder, means for supporting said cylinder for rotation about a transverse axis parallel to the axis of rotation of said table, a piston connected to one of said jaws and slideable in said cylinder, means securing the other of said jaws to said table, means for rotating the table to bring the workpiece into contact with the die and wrap the workpiece along the face of the die, and workpiece tensioning means including said piston and cylinder and a cam and follower therefor carried respectively by said table and said one of the jaws for resisting movement of said piston toward the die as said one of the jaws and the portion of the workpiece gripped thereby are drawn toward the die in response to movement of the workpiece into contact with the die and subsequent wrapping thereabout, said cam having a curved face and said follower being constrained by said tensioning means to contact and follow along said face of the cam as the workpiece is brought into contact with and wrapped along said face of the die, said cam face being shaped to control initial stretching of said workpiece by said tensioning means prior to contacting of the workpiece

with the die, said cam face being further shaped to control continual elongation of the workpiece by said tensioning means in proportion to the length of the unwrapped portion of the workpiece as the workpiece is wrapped along the face of the die, said tensioning means including a valve carried by said one of the jaws and having a spring biased plunger movable under control of said follower to a first position for preventing release of fluid under pressure by said piston in said cylinder and to a second position for releasing said fluid from the cylinder to permit movement of the piston toward the die.

4. A forming machine adapted to conform a long workpiece to a desired curvature comprising, in combination, a rotary table, a die having a face conforming to said curvature and supported on said table for rotation therewith, means including a pair of jaws respectively gripped to the ends of the workpiece and spaced from said die for holding the unformed workpiece initially away from the die, a cylinder, means for supporting said cylinder for rotation about a transverse axis parallel to the axis of rotation of said table, a piston connected to one of said jaws and slideable in said cylinder, means securing the other of said jaws to said table, means for rotating the table to bring the workpiece into contact with the die and wrap the workpiece along said face of the die, and workpiece tensioning means including said piston and cylinder and a cam and follower therefor carried respectively by said table and said one of the jaws for resisting movement of said piston toward the die as said one of the jaws and the portion of the workpiece gripped thereby are drawn toward the die in response to movement of the workpiece into contact with the die and subsequent wrapping thereabout, said cam having a curved face and said follower being constrained by said tensioning means to contact and follow along said face of the cam as the workpiece is brought into contact with and wrapped along said face of the die, said cam face being shaped to control initial stretching of said workpiece by said tensioning means prior to contacting of the workpiece with the die, said cam face being further shaped to control continual elongation of the workpiece by said tensioning means in proportion to the length of the unwrapped portion of the workpiece as the workpiece is wrapped along the face of the die.
